UNITED STATES PATENT OFFICE.

THOMAS JOSEPH MURPHY, OF ROCHESTER, NEW YORK, ASSIGNOR OF ONE-FOURTH TO
JAMES P. B. DUFFY, OF ROCHESTER, NEW YORK.

HIGH-TENSION DEVICE.

1,097,872.

Specification of Letters Patent. Patented May 26, 1914.

Application filed May 17, 1910. Serial No. 561,856.

To all whom it may concern:

Be it known that I, THOMAS JOSEPH MURPHY, a subject of the King of Great Britain, and whose residence is Rochester, State of New York, have invented certain new and useful Improvements in High-Tension Devices, of which the following is a specification.

My invention relates to high tension apparatus and it has for its object to provide a means whereby a highly attenuated discharge may be produced for affecting antennæ of a wireless telegraph or an apparatus of similar design.

15 The invention also has for its object to produce an abrupt break in a circuit carrying a large current which may be greatly multiplied in its effect in a secondary circuit.

20 The invention consists in providing electrodes adapted to carry a large direct current and means for establishing an arc across the said electrodes and causing it to suddenly rupture.

25 The invention also consists in providing electrodes across which an arc may be produced and which is gradually lengthened until it is suddenly broken down.

The invention also consists in assisting the 30 breaking down of the arc by causing it to move into a field of force.

It further consists in a means for causing it to break down at substantially equal intervals of time after starting.

35 The invention also consists in connecting an inductorium in an electric circuit having a source of supply producing a large current and allowing impulses of the current to flow through the said inductorium, the impulses being of sufficient length of time to permit it to rise to a desired amount against any counter-electromotive forces that may be established whereby the current is regulated.

40 The invention also consists in other features illustrated in the accompanying drawings and set forth in the following description.

Referring to the drawings, Figure 1 is a diagram showing the devices and connections of an embodiment of my invention. Fig. 2 illustrates an arrangement of one of the devices shown in Fig. 1.

45 1, 2 indicated in Fig. 1 are terminals of an electric circuit. The system shown is

connected to an external direct current circuit usually of 110 volts.

3 and 4 are disks which are located in proximity to each other, though not in contact. They are made of carbon or other suitable material such as pure graphite or composition containing carbon. The disks are rotated by any suitable mechanism in opposite directions, that is to say, opposing sides of the disk move in the same direction, namely, downward. The disks are connected through their bearings or through rings 5 and 6 to the terminals 1 and 2.

A condenser 7 and ball terminals 8 are connected in shunt with the disks 3 and 4. 70 The condenser 7 is connected with the disk 3 and the ball terminals are connected to the disk 4, the condenser and the terminals being connected in series. The condenser 7 is charged by an induction coil 9. The induction coil is provided with a vibrator 10 and contact 11 and operates the same as the ordinary Rhumkorff coil. The secondary 12 is connected to opposite sides of the condenser 7 and the intermittent current 75 produced in the secondary coil 12 charges the condenser 7 with a very high potential. It is discharged across the air gap of the terminals 8 and springs across the electrodes 3 and 4. The vibrator 9 and contact 11 80 of the induction coil are connected to the terminal 2. The circuit breakers 10 and 11 are also connected to the primary 13. The circuit is completed through the Morse key 14 to the terminal 1. The circuit is closed 85 by operating the key 14 in the manner well known in the art. The quantity of the current passing through the primary 13 may be if desired regulated by the resistance 15.

The oscillatory discharges produced across 90 the electrodes 3 and 4 by the sudden interruption of the current reduces the resistance between the electrodes 3 and 4 for the moment and enables the direct current produced by the difference of potential at the 95 terminals 1 and 2 to form an arc. The arc when formed continues to exist between the electrodes and permits a continuous flow of the current across the electrodes until the arc is ruptured. The opposing surfaces of 100 the electrodes moving in the same direction and at the same time away from each other, move the arc downward and gradually stretch it. When the arcs are formed they 105 produce an incandescent condition in the 110

surfaces of the electrodes at the points where they are formed and they continue to exist approximately at the points of their formation because of the low conductivity produced at that point. A large current is thus allowed to flow in the circuit of the electrodes. When the arc is ruptured the circuit carrying the large current is broken in an incredibly short interval of time, and the reaction is correspondingly large.

The electrodes 3 and 4 are connected in series with a coil 16 which forms the primary of the transformer or induction coil 17. The secondary of the transformer having a large number of turns of wire is connected to the terminals 19 and causes the production of an enormous difference of potential between the terminals 19. The highly attenuated discharge which takes place between the terminals 19 produces the waves of transmission in the manner well known in the art of wireless telegraphy.

The key 14 may be operated as desired and while its contact is closed the condenser 7 is charged and discharged intermittently which in turn produces oscillatory discharges across the electrodes reducing the resistance to practically nothing between the said electrodes which in turn causes the flashing between the terminals 19 so that when the key is operated the terminals 19 receive a highly attenuated flash. This is accomplished without destruction of instruments which are otherwise delicate and there is no volatilization of the metallic parts of the instruments and the carbon electrodes are scarcely worn in their use.

The arcs when formed between the electrodes extend at first directly across the narrow portions of the gap and they are then carried down into the field of the electromagnet 21. The intervals between the formation of the arcs and the time they are ruptured are exceedingly long compared to the length of time it requires each spark produced in the discharge of the condenser to pass across the gap between the electrodes. This will give time for a complete up-building of the current against any momentary counter-electromotive forces that may be set up in the circuit according to the rate at which the disks are rotated. If the rate is increased sufficiently the opportunity for the current to build up is reduced. The movement of the disks being substantially constant the intervals of arcing also approximate a constant. The magnet 21 has inwardly directed pole pieces 22 and 23. The field formed between the poles of the magnet is located just below and between the electrodes 3 and 4 so that as the electrodes move the arcs are carried into the field formed between the magnetic poles. The coil of the magnet may be connected in the circuit of a source of direct current or it

may be, as shown, connected across the terminals 1 and 2 of the source of main current.

A choke coil 24 may be provided for regulating or smoothing out the current. Choke coils 25 may be located in the secondary circuit for substantially the same purpose. A resistance coil 15 may be used to regulate the quantity of current and potential of the circuit of the condenser which starts the arc across the electrodes.

The structure here described and illustrated in the drawings is selected for the purpose of showing a practical application of the invention. The structure may be greatly varied by those skilled in the art and yet embody the invention. The invention may be used to accomplish a great many results and the devices which contain it may be adapted to the various purposes to which the invention is applicable.

What I claim as new and desire to secure by Letters Patent is as follows—

1. In an electric system the combination of a pair of rotatable electrodes, a source of current connected to the said electrodes and adapted to form an arc between the said electrodes, a magnet located in the vicinity of the said electrodes, means for rotating the said electrodes in opposite directions to carry the arcs formed between them into the field of force of the magnet.

2. In a wireless telegraph system the combination of an inductorium, a magnet, a pair of rotatable electrodes, a source of current connected to the primary of the said inductorium and to the said electrodes and adapted to form arcs across the said electrodes between the nearest points on the electrodes, means for rotating the said electrodes in opposite directions to stretch the arc and carry it outward and into the field of force of the said magnet.

3. In an electric system the combination of a pair of rotatable electrodes, a source of direct current connected to the said electrodes, and adapted to form an arc between the said electrodes, a magnet located in front of and between the said electrodes, the said magnet having inwardly directed poles, means for rotating the said electrodes in opposite directions to carry the arcs formed between them into the field of force produced by the magnet.

4. In a wireless system the combination of a pair of rotatable electrodes, a source of direct current, an inductorium, the primary of the said inductorium connected to the said electrodes and to the said source of current, means for starting an arc between the electrodes, a magnet having inwardly extending poles located in front of and between the said electrodes, means for rotating the said electrodes in opposite directions to carry the arcs formed between them into the field of force of the magnet.

5. In a wireless system the combination of an inductorium, rotatable electrodes, means for rotating the electrodes in opposite directions, the source of current connected to the said electrodes and to the primary of the said inductorium and adapted to form arcs between the electrodes, a magnet having its field located in the vicinity of a point between the said electrodes, 10 the said electrodes adapted to carry the arcs formed between them into the field of the said magnet.
6. In a wireless telegraph system the combination of a source of current, a pair of 15 rotatable electrodes and an inductorium located in the circuit of the said source, the primary of the said inductorium connected in series with the said source, wireless antennæ connected to the secondary of the 20 said inductorium, means for rotating the said electrodes in opposite directions, a condenser connected to the said electrodes, means for charging the condenser intermittently and means for regulating the 25 charge of the condenser across the said

electrodes thereby starting arcs between the electrodes which is maintained by the said source, a magnet, the said electrodes adapted to carry the said arcs into the field of force of the said magnet.

30

7. In a wireless telegraph system the combination of a source of current, an inductorium and a pair of rotatable electrodes located in the circuit of the said source, the primary of the said inductorium connected in series with the said rotatable electrodes, the said source adapted to form arcs across the said electrodes, a magnet located in the vicinity of the said electrodes, means for rotating the said electrodes in opposite 35 directions to carry the said arc toward the denser field of the said magnet.

35

In testimony whereof, I have signed my name to this specification, in the presence of two subscribing witnesses.

THOMAS JOSEPH MURPHY.
